CLAIM

The ornamental design for an autoload apparatus for computer disks, as shown and described.

DESCRIPTION

FIG. 1 is a slightly enlarged perspective view of the autoload apparatus for computer disks showing my new design;

FIG. 2 is a right side elevational view thereof;

FIG. 3 is a top plan view thereof;

FIG. 4 is a front end elevational view thereof;

FIG. 5 is a rear end elevational view thereof;

FIG. 6 is a bottom plan view thereof; and,

FIG. 7 is a left side elevational view thereof.

FIG. 1

FIG. 3

FIG. 4

FIG. 2

FIG. 5

FIG. 6

FIG. 7
